(57) **CLAIM**

The ornamental design for an automatic hand cleaner, as shown and described.

DESCRIPTION

FIG. 1 is a perspective view of an automatic hand cleaner, showing my new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof; and,

FIG. 8 is a perspective view of the automatic hand cleaner of FIG. 1, shown in an alternate open configuration for adding soap and/or sanitizer.

Broken lines in FIGS. 1-6 and 8 depict features of the automatic hand cleaner that form no part of the claimed design.
